UNITED STATES PATENT OFFICE.

ROBERT J. McCLELLAND, OF ELMHURST, NEW YORK, ASSIGNOR TO NATIONAL SUGAR REFINING COMPANY OF NEW JERSEY, OF LONG ISLAND CITY, NEW YORK, A CORPORATION OF NEW JERSEY.

SLUICING DEVICE.

Application filed July 12, 1921. Serial No. 434,177.

To all whom it may concern:

Be it known that I, ROBERT J. McCLELLAND, a citizen of the United States, and resident of Elmhurst, Long Island, in the county of Queens, city and State of New York, have invented certain new and useful Improvements in Sluicing Devices, of which the following is a specification.

This invention relates to a sluicing device for filter presses and has for its primary object to provide a simple and effective means for removing the coagulum or cake formation which collects upon the filter cloths of filter presses such for instance as are used in the process of refining sugar.

As is well known in the art, in the refinement of sugar, the collected material adhering to the exterior surface of the filter cloth is removed by means of wash water discharged from a pipe extending into the filter casing. This pipe is longitudinally movable and is likewise oscillated in order that the discharged water will strike the filter cloth over its entire area.

It is the primary object and purpose of my present improvement to provide a device of this nature wherein means is employed for automatically reversing the reciprocation of the wash water pipe at the end of its stroke in each direction so as to obviate the necessity of employing an attendant to manually operate the water pipe.

With the above and other objects in view, the invention consists in the improved automatic sluicing device and in the form, proportion and relative arrangement of its several parts to be hereinafter more fully described, illustrated in the accompanying drawings and subsequently incorporated in the subjoined claims.

In the drawings wherein I have disclosed one simple and practical embodiment of the invention and wherein similar reference characters designate corresponding parts throughout the several views:

Figure 1 is a side elevation partly in section showing a preferred form of the invention;

Figure 2 is a section taken on the line 2-2 of Figure 1, and

Figure 3 is a fragmentary elevation showing the manner of reversing the ratchet engaging pawl.

Referring in detail to the drawings, 5 des-

ignates the longitudinally reciprocating and oscillating wash water pipe which extends into the filter press, a portion of which is indicated at 6. The pipe 5 is connected to a fixed pipe section 7 through the medium of a sleeve 8 which is provided with suitable packing to prevent the escape of the water, while permitting of the relative movement of the pipe 5.

Upon the pipe 5 an exteriorly threaded sleeve 9 is securely fixed by one or more set 65 screws 10. A nut 11 has threaded engagement upon the sleeve 9, said nut being integrally connected at one of its ends by means of the radial arms 12 to a wheel 13 the outer peripheral face of which is provided with a continuous annular groove 14. Upon the opposite end of the nut 11 an annular flange 15 is formed and to the end face of said nut a collar 16 is rigidly fixed and has a flange 17 spaced from the flange 75 15. The space between these flanges receives a ring or annulus 18 which is connected by a plurality of bolts 19 to a fixed part of the filter press. The ring 18 thus holds the nut 11 against a longitudinal movement with relation to the sleeve 9 while permitting of its rotation upon said sleeve.

To the arms 12 of the wheel 13 a ratchet wheel 20 is securely bolted or otherwise rigidly fixed. The teeth 21 of this wheel 85 are of less width than the width of the wheel and terminate in spaced relation to its opposite side edges.

Upon the pipe 5 an arm 22 is securely fixed by means of the clamp 23 or equivalent device and in one end of this arm the pin 24 is mounted. A pawl 25 is loosely engaged upon the end of the pin 24 and to each side of said pawl and at opposite sides of the axis of the pin 24 a pair of spaced 95 lugs 26 are fixed. With the respective pairs of lugs, radially projecting fingers 27 secured upon the peripheral face of the wheel 20 at relatively opposite sides of the teeth 21 are adapted to coact in a manner to be 100 later explained.

The clamp 23 for the crank arm 22 is provided with a radially extending lever 28 upon which the collar 29 is fixed. A connecting rod 30 operated by a power driven 105 crank (not shown) is flexibly connected to the collar 29 by means of a link 31, a similar link connecting the other end of said

rod to the power crank. These links transmit an oscillating movement to the water pipe 5 in the reciprocation of the rod 30 and also permit of the longitudinal movement of said pipe. The collar 29 may be readily adjusted on the lever 28 so as to regulate the oscillation of the pipe.

It will be noted that the pawl 25 is provided at its free end and at the opposite 10 side edges thereof with lugs 32. One of these lugs is adapted to coact with the ratchet teeth 21 when the pawl is disposed at one side of the crank arm 22 as shown in full lines in Figure 2, while the other 15 of said lugs coacts with the ratchet teeth when the pawl is reversed and disposed on the opposite side of the crank arm as illustrated in dotted lines.

A friction brake band 33 is engaged upon 20 the base wall of the groove in the wheel 13, the ends of said band being connected in spaced relation to each other to a grooved wheel 34 mounted to rotate in the supporting standard 35. A horizontally extending 25 lever 36 is fixed at one of its ends to the axis of said wheel and upon the other end of said lever the weight 37 is pivoted.

In the operation of the device, when the pawl 25 is in the position shown in full lines 30 in Figure 2, upon the down stroke of the rod 30 the ratchet 20 and consequently, the nut 11 and the wheel 13 together with the pipe 5 and the sleeve 9 are given a partial rotation, the frictional resistance of the 35 brake band 33 being overcome and all of said parts moving as a unit. In the upstroke of the rod 30 the rotation of the pipe 5 is reversed and the pawl 25 moves idly over the ratchet teeth 21. In such reverse 40 movement, the ratchet 20, the nut 11 and the wheel 13 are held stationary by the brake band 33. The sleeve 9 being fixed upon the pipe 5 rotates with said pipe and with respect to the nut 11 with which said sleeve 45 has threaded engagement. The pipe and the sleeve are thus caused to move longitudinally in one direction through the nut, the extent of such movement depending upon the pitch of the threads and the operating 50 stroke of the rod 30. In this longitudinal movement of the pipe, the crank arm 22 moves therewith and accordingly, the pawl 25 is shifted longitudinally with respect to the ratchet. In the succeeding downstroke 55 of the rod 30, the rotation of the pipe 5 is again reversed and all of the parts move as a unit. It is thus seen that longitudinal movement is imparted to the wash water pipe 5 only upon the upstroke of the rod 30. 60 After one complete rotation of the ratchet 20 has been made, one pair of the lugs 26 at one side of the pawl 25 are disposed in alignment with the finger 27 at one side of the ratchet wheel so that upon the initial 65 movement of the pawl 25 in a reverse direc-

tion on the succeeding upstroke of the rod 30 one of the lugs 26 will engage the finger 27 as seen in Figure 3 of the drawings so as to kick or throw the pawl to the opposite side of the supporting pin 24 as shown in 70 dotted lines in Figure 2 whereby the ratchet will be positively rotated together with the pipe 5 and sleeve 9 in the continued upward movement of the rod. The independent oscillation of the water pipe 5 and sleeve 9 75 will now take place upon the down-stroke of the rod 30 so that the longitudinal movement of said pipe will be reversed. After a series of such operations, the longitudinal 80 movement of the pipe 5 is again reversed by the engagement of the lugs 26 at the opposite side of the pawl 25 with the finger 27 located at the other side of the ratchet 20. In this manner it will be seen that a combined oscillatory and longitudinal movement is imparted to the wash water pipe 85 and at the end of the longitudinal movement in each direction, such movement of the pipe is automatically reversed. Therefore, in the use of the device in connection with filter 90 presses, no attention whatever upon the part of the operator is required. Any desired number of oscillations of the pipe 5 may be obtained in the longitudinal stroke of the pipe in each direction by simply varying the 95 spacing of the teeth on the ratchet wheel 20 and the extent of movement of the pawl 25 in each stroke of the connecting rod 30.

I have shown the extreme positions of this pawl when actively engaged with the 100 ratchet teeth in dotted lines in Figure 2, and three such movements of the pawl are equivalent to one complete rotation of the ratchet. However, it is apparent that this is not of essential importance and the extent 105 of each of the oscillatory movements might be decreased or increased with a corresponding variation in the length of the intermittent longitudinal movements of the wash water pipe, without affecting the principle 110 of operation. By reason of the combined oscillatory and longitudinal movement of the wash water pipe, the cake formation on the surface of the filter cloth will be loosened over the entire area of the filter surface 115 and dislodged therefrom.

In the foregoing description and the accompanying drawings, I have illustrated one embodiment of the device which I have found to be very satisfactory in practical 120 operation, but it will be understood that the invention might also be produced in various other alternative forms and numerous mechanical changes made in the form, proportion and arrangement of its several parts within the spirit and scope of the invention 125 as claimed.

I claim:

1. In a sluicing device for filter presses, a water pipe, means for oscillating said pipe 130

and imparting a longitudinal movement thereto during its oscillation in one direction, and for automatically reversing the longitudinal movement of the pipe, said means including a ratchet wheel provided with teeth and having fingers projecting radially from the peripheral face of said wheel, and a pivoted pawl engaging the teeth of said ratchet wheel, and provided with spaced lugs at opposite sides of the axis of said pawl, adapted to engage the fingers of said ratchet wheel.

2. In a sluicing device for filter presses, a water pipe, means for oscillating said pipe and imparting a longitudinal movement thereto during its oscillation in one direction, and for automatically reversing the longitudinal movement of the pipe, said means including a ratchet wheel provided with teeth and with fingers projecting radially from the peripheral face of said wheel, an arm connected with said pipe and extending radially therefrom, and a pawl pivoted to said arm, engaging the teeth of said ratchet wheel, and provided with spaced lugs at opposite sides of the axis of said pawl, adapted to engage the fingers of said ratchet wheel on the rotation of said pipe.

3. In a sluicing device for filter presses, a wash water pipe, a threaded sleeve fixed thereon, a nut threaded on the sleeve, a ratchet fixed to the nut, means for oscillating said pipe, a pawl mounted upon the pipe and movable therewith circumferentially and longitudinally of the ratchet, said pawl coacting with the ratchet in the oscillation of the pipe in one direction to cause the nut to move as a unit with the pipe and said

sleeve, means for holding the nut stationary during the reverse oscillation of the pipe to thereby cause a longitudinal movement of said pipe, and means for automatically reversing the position of the pawl upon said ratchet at the end of the longitudinal movement of the pawl on the ratchet teeth in each direction.

4. In a sluicing device for filter presses, a wash water pipe, a threaded sleeve fixed thereon, a nut threaded on the sleeve, a ratchet fixed to the nut, means for oscillating said pipe, a pawl mounted upon the pipe and movable therewith circumferentially and longitudinally of the ratchet, said pawl coacting with the ratchet in the oscillation of the pipe in one direction to cause the nut to move as a unit with the pipe and said sleeve, means for holding the nut stationary during the reverse oscillation of the pipe to thereby cause a longitudinal movement of said pipe, spaced radially projecting lugs fixed to the pivoted end of the pawl at each side thereof, and a radially projecting finger fixed to each edge of the ratchet at opposite ends of the ratchet teeth with which the respective pairs of lugs are adapted to coact to reverse the position of the pawl upon the ratchet and thereby automatically reverse the longitudinal movement of the pipe.

In testimony that I claim the foregoing as my invention, and I have signed my name hereunder.

ROBERT J. McCLELLAND.
